FIG. 5

FIG. 7

FIG. 8

FIG. 9

FIG. 1 is a perspective view of a first embodiment of our design for a base of a telephone set;

FIG. 2 is a left side view of the base of FIG. 1;

FIG. 3 is a perspective view of a second embodiment of our design for a base of a telephone set;

FIG. 4 is a left side view of the base of FIG. 3;

FIG. 5 is a perspective view of a third embodiment of our design for a base of a telephone set;

FIG. 6 is a left side view of the base of FIG. 5;

FIG. 7 is a perspective view of a fourth embodiment of our design for a base of a telephone set;

FIG. 8 is a left side view of the base of FIG. 7; and

FIG. 9 is a rear view of the base that is the same for all four embodiments.

The broken line indicia disclosed in FIGS. 1 and 3 on the drawing is shown for illustrative purposes only.

This is a continuation-in-part of design application Ser.

No. D. 11,857, filed May 9, 1968, abandoned subsequent to the filing of this application.

We claim:

An ornamental design for a base of a telephone set, substantially as shown and described.
